SHOE

Frederick P. Wagner, St. Louis, Mo., assignor of
one-half to Arthur J. Brauer, St. Louis, Mo.

Application August 30, 1935, Serial No. 38,495

9 Claims. (Cl. 36—45)

This invention relates generally to shoes and particularly to an improved throat construction for shoes.

An object of the present invention generally stated is to provide a shoe of the oxford type in which the throat construction is such as to avoid binding and biting thereat so as to improve the comfort of the shoe.

A further object of this invention is to provide a shoe construction in which the lace stays do not interfere with the yieldability of the shoe.

The more specific object of this invention is to provide a shoe of the oxford type in which a yieldable throat portion is so related to the construction and arrangement of the lace stays that the action of the yieldable throat portion is uninterfered with.

Other objects will become apparent to those skilled in the art when the following description is read in connection with the accompanying drawings in which:

Figure 1 is a perspective view of a shoe embodying the features of the present invention.

Figure 2 is a sectional view taken along line 2—2 of Figure 1 and showing the parts in exaggerated relation.

Figure 3 is a plan view of the shoe shown in Figure 1, part being broken away to expose the relation of the parts.

Figure 4 is a sectional view taken along line 4—4 of Figure 3 the parts being shown in exaggerated relation.

Figure 5 is a sectional view taken along 5—5 of Figure 3 the parts being shown in an exaggerated relation.

Figure 6 is a plan view of another embodiment of the invention parts being broken away to show the relations of the parts.

Figure 7 is a sectional view taken along the 7—7 of Figure 6 and showing the parts in exaggerated relation.

Figure 8 is a plan view of a further embodiment.

Generally stated in accordance with the present invention a shoe of the oxford type which is provided with a yieldable throat portion may have its lace stays so constructed and arranged as to underlie the throat portion and hence produce a bal oxford effect. In accordance with the present invention, however, the underlying lace stays are left disconnected or not directly connected to the throat section so that the stiff unyieldable throat characteristic of the bal oxfords is avoided. In the latter respect, therefore, the yieldability of the shoe is comparable

to that of the ordinary blucher oxford. In order to further increase the comfort of the shoe the throat portion may be rendered yieldable in any desired manner.

In accordance with one embodiment with the present invention the shoe may be constructed as is usual with blucher oxfords and be provided with a yieldable throat portion, but have the noses of the lace stays turned inside of the throat portion of the upper, instead of outside as is the usual practice. In accordance with another embodiment, however, the shoe is constructed along the lines of the conventional bal oxford construction but the lace stays are left free adjacent the throat. If the shoe is also provided with a yieldable throat full advantage of the yieldability may be taken because the connection of the lace stays do not interfere.

Referring now particularly to Figures 1 to 5 inclusive of the drawings, for one illustrative embodiment, the shoe may be provided with an exterior vamp section 1 having a throat region 2. In accordance with the present invention the throat region 2 is made yieldable in any desired manner. For instance the shoe may be provided with the construction shown and described in U. S. Patent #2,005,071, to Frederick P. Wagner, or the shoe may be rendered yieldable in this region by other known means as for instance by omitting any reinforcement material thereat, so as to take advantage of the natural yieldability of the leather or other material from which the shoe may be made.

Being a shoe of the oxford type the shoe shown in Figure 1 is also provided with a pair of lace stays 3, which may be a part of the quarter section 4, or may be separately formed as desired.

The shoe may also be suitably lined and to that end may be provided with a doubler 5 for the exterior vamp section 1 and a doubler 50 for the lace stays 3. The shoe may also be provided with a lining 6 which may be of any suitable material such as fabric or leather. In the present embodiment the lining 6 may be considered as fabric and provided with a throat lining 7 of leather or other suitable material. The lace stays 3 may also be composed of an exterior section 8 and a suitable lining 9 together with reinforcing strips 10, or otherwise formed as desired.

In constructing the shoe in accordance with the present invention, after the throat portion of the vamp 1 has been formed so as to provide yieldability, as for instance, in accordance with the disclosure of U. S. Patent #2,005,071, by pro-

viding a strip of resilient material 11 such as elastic in a fold 12 at the throat portion, the lace stays 3 may be assembled and connected so as to underlap the yieldable throat portion 2, as clearly shown in Figure 4. In the embodiment illustrated the lace stays are formed integrally with quarter section 4, and hence may be connected to exterior upper section 1 forming the vamp by lines of stitching 13 extending along beyond the end of the yieldable throat portion 2 to each side thereof. A second line of stitching 14 may also be provided extending completely across throat portion as clearly shown in Figure 1. In accordance with this invention, however, 15 the lace stays 3 are connected to the vamp section 1 only by means of lines of stitching 13, which as stated above terminate at the ends of yieldable throat section 2, so that medially of the throat the lace stays are disconnected from the 20 exterior vamp section 1. Line of stitching 14 may, however, extend through and catch throat lining 7 medially of the yieldable throat portion 2. This, however, leaves a sufficient yieldable area therebeyond to prevent the shoe from biting 25 at the throat.

A suitable tongue 15 may be connected to the lining ahead of the terminus of lace stays 3 as by lines of stitching 16, or otherwise. When connected in this manner the tongue may extend 30 back over the ends of the lace stays, and thus prevent any discomfort which might otherwise be occasioned by the abrupt ending of the lace stays. It will be understood, of course, the end 35 of tongue 15 where it is joined to the lining by stitching 16 is suitably skived and folded to form a smooth, neat joint, not of the abrupt character shown in Figure 4, it being realized, of course, that the proportion and thickness of material as shown in Figure 4 are considerably exaggerated 40 so as to clearly depict the relation of the parts.

As is usually the case with shoes of this type, the quarter section 4 with the lace stays 3 is arranged so as to be contiguous with the margin of vamp section 1 where the two are joined together, that is to say along the sides of the shoe where the quarter and vamp are joined by line of stitching 13, the quarter is interposed between the vamp and its lining 6. In view of the fact, however, that the lace stays according to the present 45 invention are intended to underlap the throat portion of the shoe, provision is made for permitting the lace stays to pass through to the underside of the throat lining 7. This may be accomplished by providing slits 17 in the quarter at 50 that portion of the ends of the lace stays 3 which will lie adjacent the ends of the yieldable throat portion 2. This permits throat lining 7 to pass beneath the quarter 4 outwardly beyond the slits 17 but between slits 17 the throat lining 7 passes 55 above the exterior section 8 of lace stays 3 as clearly shown in Figure 5. In the construction thus provided the throat lining 7 is drawn up next to the vamp without interfering with the 60 looseness of the lower ends of the lace stays at this point.

Referring now to Figures 6 and 7 for a further 65 illustrative embodiment of the present invention the parts in general correspond to the arrangement of the embodiment previously described. In the present embodiment, however, the ends of lace stays 3 instead of being entirely disconnected from the exterior vamp section 1 in the 70 region of yieldable throat portion 2 are connected to the lining for the exterior vamp section 1

medially of the shoe, but substantially ahead or in front of the yieldable throat portion 2.

In carrying out the invention in accordance with this embodiment the line of stitching 13 is, as in the previous embodiment, terminated at 5 the end of throat portion 2, so that the quarter or lace stays 3 is not directly connected to the exterior vamp portion 1 medially of yieldable throat section 2. In accordance with this embodiment, however, lining 19 for the lace stays 10 3 (corresponding to lining 9 in the previous embodiment) is extended forwardly for a sufficient distance to be connected with lining 6 substantially ahead of yieldable throat portion 2. The relation of the parts is clearly shown in Figure 7. 15 It will be understood, therefore, that lining 19 takes the place of throat lining 7 in the previous embodiment, but instead of continuously extending across the throat portion, as was the case with lining 7 of the previous embodiment, it will 20 be noted that lining 19 is parted medially of the shoe as shown at 22. By thus medially parting the lining at the throat greater flexibility is achieved so that connection of the quarter and 25 lace stay lining 19 to the vamp lining 6 ahead of the yieldable throat portion does not substantially reduce the yieldability of the throat portion, and a comfortable shoe is produced.

Referring now to Figure 8 a shoe is shown in which the throat region is not provided with the 30 particular yieldable construction illustrated in the two previous embodiments and shown and described in U. S. Patent #2,005,071. In the embodiment shown in Figure 8 the throat portion is made plain, but as shown line stitching 13 35 terminates as in the previous embodiment at 20 so as to leave a central region 21 at the throat which is devoid of reinforcing or stitching, and hence the leather itself is free to yield thereat, provided no reinforcing means is applied which 40 would prevent the leather from stretching naturally. The shoe of this embodiment may, of course, be constructed in accordance with either of the other two embodiments as far as lace stay connection is concerned, that is to say, the 45 lace stays may be left entirely free at the medial portion of the throat or may be connected through the lining substantially ahead of the yieldable portion as desired.

As clearly shown in Figure 1 the shoe of any or 50 all of the embodiments of the present invention may, if desired, be provided with a yieldable back or counter section 24 as shown in accordance with the disclosure of my co-pending application, Serial No. 21,073, filed May 13th, 1935, now Patent 55 Number 2,061,746, granted Nov. 24, 1936.

Although in each of the embodiments specifically described hereinbefore a special provision has been made for rendering the upper yieldable in a region of the throat, it is to be understood 60 that a shoe of increased comfort over the conventional bal oxford may be obtained without such special provision for yieldability of the throat. By leaving the ends of the lace stays free for movement relative to the vamp or throat 65 a more flexible shoe is obtained, and one which is less harsh to the foot in the region of the throat than the ordinary bal oxford. Accordingly, it is to be understood that the open bal type oxford construction herein described is not limited to 70 use in connection with uppers having yieldable throats.

From the foregoing description it should be apparent that the invention accomplishes its objects and provides a shoe of the oxford type in 75

which a yieldable throat construction is provided, and the action of the yieldable throat construction is not interfered with by the construction and arrangement of the lace stays. The invention further provides a shoe which, although, unrestrained by the lace stays as the case with the usual blucher, nevertheless presents the neat appearance of the well known bal oxford. In accordance with the various embodiments this is accomplished by leaving the ends of the lace stays free of direct connection to the exterior upper in the region of the throat.

From the foregoing description it will be apparent that many modifications of the shoe and process of making the same, as herein disclosed will present themselves to those skilled in the art without departing from the spirit of this invention. It is to be understood, therefore, that the invention is not limited to the foregoing description of illustrative embodiments, but possesses features applicable to the manufacture of shoes generally. It should be understood, therefore, that such modifications, or the use of such individual features or sub-combinations of features as do not depart from the spirit of this invention are, although not specifically described herein, contemplated by and within the scope of the appended claims.

Having thus described the invention, what is claimed is:

1. A shoe of the oxford type comprising, an exterior upper section having a throat line, lace stays connected to the upper section, said lace stays underlapping the throat line of the upper and being free of direct connection to the throat portion of the upper.

2. A shoe of the oxford type comprising, an exterior upper section having a throat line, lace stays connected to the upper section in regions remote from the throat line, said lace stays underlapping the throat line of the upper and being free of direct connection to the upper for a substantial distance at the throat line.

3. A shoe of the oxford type comprising, an exterior upper section having a throat line, lace stays connected to the upper in regions remote from the throat line and underlapping the throat

line, said upper and lace stays being free of direct connection adjacent the throat line.

4. A shoe of the oxford type comprising, an exterior upper section having a throat line, lace stays underlapping the throat line and connected to the exterior upper section only at points a substantial distance from the middle of the throat line.

5. A shoe of the oxford type comprising, an exterior upper section having a throat line, a lining for said upper section, lace stays, said lace stays being connected to said lining but being free of direct connection with the exterior upper section at the throat line of the shoe.

6. A shoe of the oxford type comprising, an exterior upper section having a throat line, a lining for said upper section, lace stays, said lace stays being disconnected from the exterior upper section medially of the throat line and connected to the lining substantially ahead of the throat line.

7. A shoe of the oxford type comprising, an exterior upper section having a throat line, a lining for said upper section, lace stays having an exterior section and a lining, the lower end section of said lace stays being interposed between the upper section and its lining at the ends of the throat line but underlying the lining and upper section at the median portion of the throat line, said lace stays being free of direct connection to the exterior upper section at the throat line thereof.

8. A shoe of the oxford type comprising an exterior upper section having an unreinforced throat portion, and lace stays underlapping said throat portion, and disconnected from the upper section medially of the throat portion.

9. A shoe of the oxford type comprising an exterior upper section having an unreinforced marginally continuous throat portion, a lining for said section parted adjacent the throat line, and lace stays underlying said throat portion and connected to said lining but disconnected from said exterior upper section medially of the throat line.

FREDERICK P. WAGNER.
